UNITED STATES PATENT OFFICE.

CHARLES H. MASCHMEYER, OF PORTLAND, MAINE.

HANDLE.

No: 822,970.

Specification of Letters Patent.

Patented June 12, 1906.

Application filed November 18, 1905. Serial No. 287,951.

To all whom it may concern:

Be it known that I, CHARLES H. MASCHMEYER, a citizen of the United States, residing at Portland, in the county of Cumberland 5 and State of Maine, have invented new and useful Improvements in Handles, of which the following is a specification.

This invention relates to improvements in handles for receptacles for containing hot liquids, and more particularly relates to means for insulating the handle, so as to prevent the transmission of heat from the receptacle to the handle, and it relates more particularly to an improvement on the invention described in Letters Patent No. 485,846, dated November 8, 1892, issued to me, in which the handle is insulated from the receptacle by non-metallic inserts held in place by non-metallic bonds with roughened surfaces. In actual practice it is found that where the bond and the inserts are of non-metallic material it is well nigh impossible to fuse the metal of the handle around the insert and bond so as to make a tight joint, the handle part working loose and the non-metallic bond being liable to be broken.

The object of my invention is to overcome these objections.

In the drawings herewith accompanying 30 and making a part of this application, Figure 1 is a side elevation of a receptacle with my improved handle applied thereto. Fig. 2 is a vertical sectional view of the handle, showing the insulating - inserts and metallic bonds, one in section and the other in elevation; and Fig. 3 is a plan view of the non-metallic insert.

In said drawings, A represents any form of receptacle. The handle is composed of the 40 parts B B, joined to the receptacle in any convenient way, and C the hand portion

proper of the handle. Inserted between the parts B B and C are non-heat-conducting inserts D. The parts of the handle B B and C and the inserts D are bonded together by metallic bonds having an attenuated body part 45 E, with enlarged ends F.

In the process of manufacture the inserts, with the bonds, are placed in a suitable mold and the metal flowed against the inserts and 50 around the bonds, the metal forming a strong union between the sections of the handle and the bonds, thus holding the sections of the handle closely against the insert. The inserts may be provided on either side with indentations G, into which the metal flows during the process of forming up the handle, thus preventing any rotary movement of the insert relative to the handle. It is found in actual experience that the long attenuated 55 body portion of the bond, although a conductor of heat, is insufficient to conduct heat enough to the hand portion of the handle to be at all objectionable.

Having thus described my invention and 60 its use, I claim—

A handle for receptacles consisting of attachment-sections, a hand-section, insulating-inserts between the adjacent ends of the sections and a metallic bond having an attenuated body portion and enlarged ends, the body portion passing through the insert and the enlarged ends embedded in the metal 70 of the section.

In testimony whereof I have signed my 75 name to this specification, in presence of two subscribing witnesses, this 14th day of November, 1905.

CHARLES H. MASCHMEYER.

In presence of—

ELGIN C. VERRILL,
MARION RICHARDS.
